CLAIM

The ornamental design for a tray, as shown and described.

DESCRIPTION

FIG. 1 is a perspective view of a first embodiment of a tray showing our new design;

FIG. 2 is a top view of the design shown in FIG. 1;

FIG. 3 is a bottom view of the design shown in FIG. 1;

FIG. 4 is a right side view of the design shown in FIG. 1, wherein the left side view is identical to the view in FIG. 4; FIG. 5 is a front view of the design shown in FIG. 1, wherein the back view is identical to the view in FIG. 5;

FIG. 6 is a perspective view of a second embodiment of a tray showing our new design;

FIG. 7 is a top view of the design shown in FIG. 6;

FIG. 8 is a bottom view of the design shown in FIG. 6;

FIG. 9 is a right side view of the design shown in FIG. 6, wherein the left side view is identical to the view in FIG. 9; and,

FIG. 10 is a front view of the design shown in FIG. 6, wherein the back view is identical to the view in FIG. 10. The broken lines illustrate portions of the tray and form no part of the claimed design.

1 Claim, 8 Drawing Sheets
